(57) **CLAIM**

The ornamental design for the digital multifunction printer, as shown and described.

DESCRIPTION

FIG. 1 is a perspective view of a digital multifunction printer showing our new design;

FIG. 2 is a second perspective view of the digital multifunction printer;

FIG. 3 is a front elevation view of the digital multifunction printer;

FIG. 4 is a rear elevation view of the digital multifunction printer;

FIG. 5 is a right side elevation view of the digital multifunction printer;

FIG. 6 is a left side elevation view of the digital multifunction printer;

FIG. 7 is a top plan view of the digital multifunction printer; and,

FIG. 8 is a bottom plan view of the digital multifunction printer.

The dot-dash broken lines and evenly spaced broken lines immediately adjacent to the shaded areas depict the bounds of the claimed design, while all other evenly spaced broken lines are directed to environment. The broken lines form no part of the claimed design.

The item is a multifunctional machine that combines the functions of a copier, scanner, and printer.
